UNITED STATES PATENT OFFICE

2,237,795

ELECTRIC RANGE

Jacob L. Shroyer, Oak Park, Ill., assignor to Edison General Electric Appliance Company, Incorporated, Chicago, Ill., a corporation of New York

Application December 21, 1937, Serial No. 181,014

5 Claims. (Cl. 219—37)

This invention relates to electric ranges, and it has for its object the provision of an improved device of this character.

While not limited thereto, this invention is particularly applicable to heavy duty electric ranges such as used in hotels, restaurants, ships and the like, and it has for its object the provision of a general utility range of this character which is provided with quick heating, high temperature surface heating units, surface hot plates and griddles, and an oven. This invention contemplates a range of this character which is relatively simple and inexpensive in its construction, convenient and easy to use, and which is easily kept in proper working order and in a clean condition.

For a more complete understanding of this invention, reference should be had to the accompanying drawings in which Fig. 1 is a front elevation of an electric range embodying this invention, parts being broken away so as to illustrate certain details of construction; Fig. 2 is a plan view of the electric range of Fig. 1 with parts broken away so as to illustrate certain details of construction; Fig. 3 is a vertical sectional view taken through the line 3—3 of Fig. 1 and looking in the direction of the arrows; Fig. 4 is a vertical sectional view taken through the line 4—4 of Fig. 2 and looking in the direction of the arrows; Fig. 5 is a fragmentary view in section taken through the line 5—5 of Fig. 1 and looking in the direction of the arrows; and Figs. 6 and 7 are perspective views illustrating oven and top plate sections used in the electric range of Figs. 1—5 inclusive.

Referring to the drawings, this invention has been shown in one form as applied to an electric range of the heavy duty type having a cooking top plate section 10 and an oven section 11 below it. It is to be understood that the parts 10 and 11 are separable and each may be used independently of the other, but in the form of the invention illustrated the two parts are shown as incorporated in the same range structure, the cooking top 10 being placed upon and supported by the oven section 11.

The cooking top section 10 comprises a compartment defined by a pair of side walls 12, a rear wall 13, a top plate 14, and a front wall formed by a series of panels 15; in the specific cooking section 10 disclosed there are three front panels 15. The side and rear walls are provided at the bottom with inturned flanges 12a and 13a.

The top plate 14 is provided with a relatively large rectangular opening 16 through which the

heating or cooking elements 17 (Fig. 7) are received. The cooking elements 17 in the form of the invention shown in the drawings comprise two high temperature, quick heating elements 18, two lower temperature hot plates 19 and a relatively large heavy duty griddle 20. All of these elements are removable, and it is to be understood that their proportions are such that they may be interchanged one for the other. 10 For example, the griddle 20 may be dispensed with and in its place there may be used two high speed surface units 18, or two hot plates 19, or one of one and one of the other. Moreover, if desired, one each of the elements 18 and 15 19 may be eliminated and a very large griddle used in place of them and of the smaller griddle 20. Preferably, the heating members 18 and 19 will be substantially square.

Each high speed, high temperature heating element 18 comprises a plurality, more specifically, a pair of sheathed heating elements 21 and 22 supported on a grid 23 which in turn is supported by a top plate 24. The top plate 24 is provided with an opening 25 in which the heating elements 21 and 22 are received, and at this opening 25 there is a down-turned flange 26 on the top plate 24. This down-turned flange is provided with longer depending tabs 27 in which the ends of the grids 23 are received. The plate 24 is provided at its peripheral edges with a down-turned flange 27 which functions to support the top plate and the heating elements mounted in it. The down-turned flange 27 is mounted upon brackets 28 at their front corners; these brackets are rigidly secured to a flange 16a extending downwardly from the top plate 14 around the opening 16. At the rear sections of the heating units 18, as well as at the front, the down-turned flanges 27 rest upon beams 29 extending cross-wise of the range from side to side and spaced at intervals from the front to the rear, as clearly shown in Figs. 2 and 3.

45 The heating elements 21 and 22 may be of any suitable type, but preferably will be of the sheathed type such as described and claimed in United States patent to C. C. Abbott No. 1,367,341, dated February 1, 1921. Briefly, these heating elements comprise a resistance conductor (not shown) mounted in a metallic sheath 30 (Fig. 4), and supported in spaced relation with reference to the sheath by a suitable powdered heat-conducting, electrically-insulating material (also not shown). Terminal sections 31 of the heater are brought out laterally from the unit

18, as shown in Figs. 2 and 4 and in the ends of these sections suitable terminals 31a are mounted. To these terminals suitable electrical supply leads 32 are connected. In order to protect the terminals 31a and the leads 32 and the electrical connections between these members from the grease, liquids and the like drippage from vessels placed on the range, the terminal sections 31 are directly upwardly and thence downwardly, as clearly shown in Fig. 4. This 10 prevents grease and liquids from running along the sheathed heater to its terminals. As a further protection, the sheathed heaters are provided with washers or baffles 33 adjacent their ends to intercept any grease or liquid which 15 might possibly run along the heaters.

In addition, each of the heating elements 18 is provided with a reflecting pan 34 which houses the heating elements 21 and 22 as well as the grids 23, as clearly shown in Fig. 4. The reflecting pan is provided with a bottom wall 35 in which there is a centrally arranged depressed section 36 having its bottom sloping to the center where a drain opening 37 is provided. This pan at one edge is provided with a cut-away section 38 through which the terminal ends 31 of the heater project laterally from the heating element. The reflector 34 rests upon the supporting beams 29 which are provided with cut-away sections 39 (Figs. 2 and 4) to receive the reflector, as clearly shown.

It will be observed in view of the foregoing construction that the heating elements 21 and 22 with their grid 23 and top 24 may be removed from the top of the range, and so also may the reflector 34 so that these elements can be conveniently cleaned and replaced.

The reflectors may be conveniently removed by tilting up the edges of the heating elements at their terminal edges on the brackets 28 and then withdrawing the reflectors laterally, the brackets 28 constituting auxiliary supporting means provided for this purpose. The leads 32, as shown, are sufficiently long to permit the heating elements 18 to be elevated a sufficient distance from the cooking top to provide room for cleansing them. If desired the flange 27 on the plate 24 may be provided with extensions 27a (Figs. 2 and 4) opposite the terminal side of the heating element and arranged to closely fit opposite sides of the beams 29. This holds the heating element in place.

The hot plate 19 comprises a rectangular mass 40 formed of any suitable heat conducting material, such as cast iron. This mass is provided with a ground and polished cooking surface 41 (Fig. 4). Cast within the body 40 are one or more sheathed heating elements 42 of substantially the same type described above in connection with the heating plate 18. The plates 19 also are supported on the brackets 28 and 29, as shown in Figs. 2 and 4. Here also, the terminal ends 42a of the heating elements 42 are directed upwardly and then downwardly to protect the terminals 43, and here also, the heaters preferably will be provided with intercepting baffles 44 to further protect these terminals. Leads 44a similar to the leads 32 are connected to the terminals 43.

The griddle 20 is in general of the same construction as the plate 19 having a heating body 45 formed of a suitable heat conducting material, such as cast iron, and in which the sheathed heating elements 46 are cast. These units have substantially the same construction

as described in connection with the plates 18 and 19, and they are connected to suitable leads 46a. The griddle 20, however, is provided with a grease trough 47 extending along its sides and front, as shown in Figs. 2 and 3. The grease and liquids draining off of the griddle during the cooking operations collect in this trough and drain through a discharge spout 48. Arranged within the compartment of the top cooking section is a greased drawer 49 which collects the discharge from the spout 48. The drawer 49 slides in a guideway or slide 50, and as shown more clearly in Figs. 1 and 7, is accessible at the front of the range. As shown in these figures, this drawer may be withdrawn through the right-hand panel 15 so that it may be emptied and replaced.

The beams 29 are supported at their ends by U-shaped brackets 51 which at their upper ends are directed through openings provided for them in elongated brackets 52 secured to the side walls 12 in any suitable manner, as by welding. On the upper ends of the legs of the brackets 51 are nuts 51a (Fig. 2) which are turned in tightly to hold the beams 29 in place.

Mounted within the front wall panels 15 of the top cooking section are four switches 53 for controlling the four heating elements 18 and 19. Also there is a switch 54 for controlling the energization of the griddle 20. Preferably, the switches 53 are of the multiple position type arranged to control the heating elements of the plates 18 and 19 to provide high, low and medium heats. The griddle 20 is further controlled by means of a thermostat 55 to hold a substantially constant selected temperature in the griddle. This thermostat may be of any suitable type, such as the bulb and bellows type. The bulb 56 of this thermostat is shown in Fig. 3 embedded in the heating mass 45 of the griddle.

The electrical supply leads 44a of the rear plates 19 and the leads 46a of the griddle are directed forwardly from the rear of the upper cooking compartment to the front where the switches are located through a conduit 57 (Figs. 1, 2 and 7). The rear leads 44a and 46a are supported in insulating clips 58 attached to the rear wall 13 of the cooking compartment, while the leads 32 at the front are supported by insulating clips 59. These clips 59 are attached to a cross beam 60 that is supported at its opposite ends on brackets 60a (Fig. 1) attached to the side walls 45 of the cooking section.

Mounted in the bottom and at the front of the upper compartment 10 is a transverse member 61 which has several functions among which are to secure the lower ends of the panels 15, and to support a cut-out or fuse structure used in the cooking sections. The member 61 at its ends is provided with end walls 62 (Fig. 1) that are welded or otherwise suitably secured to the end walls 12 of the top section. The member 61 is provided at its top with a horizontal wall 63 which in turn at its forward end has a down-turned flange 64, over which the lower hook-like ends of the two outside panels 15 are fitted, as clearly shown in Fig. 3. The upper ends of these outer panels are attached to brackets 65 by means of screws 66. The brackets 65 are attached to the cross beam 60 in any suitable manner, as by welding.

Also mounted on the top wall 63 of the front member 61 is a suitable fuse or cut-out box 67 for the cooking elements 18, 19 and 20 which is arranged in the center of the cooking section

back of the center panel 15. The cut-out box 67 is mounted on a supporting bracket 67a which in turn is secured directly to the top wall 63 by means of a pair of spaced arms 68, one of which is shown in plan in Fig. 2. The center panel 15 opposite the fuse box is hinged at its bottom to the member 61 and is bised to its closed position by means of a spring 69.

In order to protect the switches 53 and 54 and the cut-out 67 from an abnormal temperature rise, I provide in the compartment of section 10 suitable baffles 70 and 71 between them and the high temperature zone below the heating elements 18, 19 and 20. The baffles 71, as shown in Fig. 3, are located at the front of the high temperature zone directly below the heating elements, and are positioned angularly to the vertical, that is, downwardly toward the rear, in such a way as to tend to pocket the hot air in this zone to prevent its free circulation toward the front where the switches and cut-out are located. It further functions to shut off radiation from these heating elements 18, 19 and 20 in the direction of the switches and cut-out. The second set of baffles 70 also is inclined downwardly toward the rear, and also acts as an insulating barrier to assist the baffle 71 to prevent the direct radiation of heat to the switches and cut-out; and in addition, it cooperates with the baffles 71 to localize a second lower temperature heat zone between the high temperature zone and the switches and cut-out; that is, these baffles also function to prevent a secondary circulation of air in the front portion of the upper cooking section. The baffles 71 are supported directly from the adjacent cross-beam 29, while the baffles 70 are supported on arms 72 (Figs. 2 and 3) that are mounted on the top wall 63 of the member 61. It will be observed that the baffles 70 and their supporting arms 72 are substantially separated from the supporting structure 67a, 68 that mount the cut-out 67, the only connection between these members being through the top wall 63.

In addition to the baffles which prevent radiation and the circulation of hot air to the switches and cut-out, suitable means are provided for directing cooling air into the upper cooking section over the switches and cut-out and through the section to keep the section at a moderately low temperature. The ventilating system comprises an elongated ventilating opening 73 in the transverse member 61 through which the cooling air may enter the top plate cooking section. The air that enters the opening 73 may take several paths: It may pass directly upwardly over the switches 53 and 54 and the cut-out 67 to the upper part of the front section where it is discharged through louvers 74 provided in the upper part of the panels 15, as indicated by the arrows a; if desired the front panels may also be provided with lower louvers 75 through which cooling air may enter at the bottom and flow into the stream a. A second path b for the cooling air is back to the rear of the upper top plate cooking section where it is discharged at the top through a discharge hood 76. This second path, as shown, directs the cooling air back under the baffles 70 and 71 and under the cooking elements 18, 19 and 20 to the rear for discharge through the hood. This second path maintains a reasonably low temperature within the upper section. The cooling air in path a at the front may also discharge through an opening at the top between the upper edges of the 75

front panels 15 and the top plate 14. Preferably, the top plate will be provided with a lower downwardly extending flange 77 to conceal this opening. Moreover, as clearly shown in the drawings, the baffles 70 are spaced apart; and the succeeding baffles from the front to the rear extend closer to the bottom of the compartment so that part of the air stream entering the front of the compartment impinges on the lower ends of the baffles and is caused thereby to flow upwardly through the spaces between the baffles, as indicated by the arrows c. This further thermally insulates the switches and cut-out from the hotter zones of the compartments.

Arranged within the top section and below the heating elements 18, 19 and 20, and the grease drawer 49 is a large shallow drip pan or drawer 78 which may be withdrawn forwardly of the range through the opening 73 provided in the transverse member 61. The pan 78 is provided at the sides with guides 79 attached to the side walls 12 of the top section, and at the front is provided with a transverse handle 80. The handle 80 is of baffle-like form, as shown, inclined downwardly from the member 61 and over-hanging the oven section 11. The handle acts as a baffle or shield to deflect hot gases rising from the oven outwardly away from the ventilating opening 73 through which the cooling air enters the top section.

The tray 78 is thermally insulated from the switches 53 and cut-out 67. The tray, as shown, terminates at the front substantially at the baffle 70. In other words, it does not extend completely to the front of the top section, but terminates at a point well back of the switches 53 and cut-out 67. The tray is connected to the handle 80 by means of relatively small spaced straps 81. The bottom of the pan 78 is subjected to rather intense radiation from the heating elements and attains a relatively high temperature. But it does not impart heat to the switches and cut-out inasmuch as its front end terminates short of these members. The relatively small straps 81 connecting the pan to its handle 80 cannot conduct any substantial amount of heat from the hot pan to the switch, cut-out section.

The oven section 11 is substantially of box-like form having an outer lining defined by top and bottom walls 82 and 83, side walls 84, an end wall 85 and a front wall 86. The oven chamber 87 has top and bottom walls 88 and 89, side walls 90, and a rear wall 91 spaced from the corresponding top, bottom, side and end walls of the outer section. Preferably, a second rear wall 92 will be provided for the oven spaced outwardly from the first so as to leave a space 92a at the rear of the oven. A layer of heat insulating material 93 is placed around the oven chamber 87.

At the front, the oven chamber is closed by a door 94 which is hinged at the bottom to swing outwardly to an open position. At the top, the door is provided with a handle 95. The door is provided with inner and outer complementary linings 96 and 97 which are fitted together and secured in any suitable manner. At the bottom, the door is mounted on shafts 98 which are mounted in brackets 99. The door is counter-balanced and held in its closed position by means of a spring 100 attached at one end to an anchor 101 and at its opposite end to a flexible strap 102 which is directed over an idler pulley 103 and attached to one side of a quadrant-shaped bracket 104. This bracket is attached to

the right-hand shaft 98 of the door, as viewed in Fig. 1. When the door is moved from its closed position of Fig. 5 to its open dotted-line position of this figure, the bracket 104 is moved to its dotted-line position, and when it does so, it tensions the spring 100 to counter-balance the door as it moves to the open position. Conversely, when the door is moved to its closed position it is counter-balanced and is held in its closed position by the tension of the spring 100.

Upper and lower heating elements 105 and 106 are provided in the oven. An oven rack 107 is interposed between these heating elements and at the bottom a deck 108 is provided over the lower heating element. The heating elements are provided at the rear with terminals 109 which are received in sockets 110. The energization of the two heating elements is controlled by means of switches 111, and the oven temperature is controlled by means of a thermostat having an adjusting knob 112 accessible at the front of the oven. As shown, the switches 111 and the temperature control knob 112 are located at the right-hand end of the oven, as viewed in Figs. 1 and 7, and under these members is a door 13 hinged at the bottom and biased to its closed position by a spring 114. Back of this door are located the protective fuses or cut-outs for the oven. The electrical supply leads for the oven are directed through an opening 115 (Fig. 6) in the bottom wall 83 of the oven, and when the top section 10 is placed upon the oven, as shown in the drawings, the supply leads for the upper cooking sections are also directed upwardly through the opening 115. Those for the upper section are passed out of the oven section through its top wall 82 through an opening 116 (Fig. 6) which is provided by forcing outwardly a knock out 117. An opening 118 is provided in the top section that registers with the opening 116 and through which the supply leads are directed into the conduit 57 of the upper section.

The top section is provided with feet 119 which are received in knock outs 120 provided for them in the oven section to locate the top section in proper position on the lower.

The vertical space 92a back of the oven heating chamber is ventilated by cooling air which enters the bottom through openings (not shown) in the bottom wall 83 and which passes freely upwardly and out at the top through openings 121. These openings discharge directly into the top section where the ventilating air is discharged through the hood 76. The oven is vented through a ventilating tube 122 which at its lower end is connected with the oven, and at its upper end with an opening 123 which also communicates with the ventilating system of the top section. A damper 124 is provided in this flue and is controlled by means of a rod 125 which extends forwardly to the front of the oven where an operating knob 126 is provided.

The specific structure of the heating elements 17 involving improvements in the terminal structure, the reflectors, and the means for supporting the heating elements and reflectors is described and claimed in my copending application, Serial No. 237,518, filed October 28, 1938, which application is a division of this application.

While I have shown a particular embodiment of my invention, it will be understood, of course, that I do not wish to be limited thereto since many modifications may be made and I, therefore, contemplate by the appended claims to

cover any such modifications as fall within the true spirit and scope of my invention.

What I claim as new and desire to secure by Letters Patent of the United States is:

- 5 1. In an electric range having a top plate and heating elements in said top plate, controlling elements for said heating elements located at the front of and below said top plate, a metallic drip tray below said heating elements having its front edge terminating considerably to the rear of and below said controlling elements so that heat imparted to said drip tray from said heating elements is not radiated and conveyed to said controlling elements, a handle for said tray below said controlling elements accessible at the front of said top plate, and relatively low heat conducting members connecting said handle with said tray.
- 10 2. In an electric range having a top plate and heating elements in said top plate, controlling elements for said heating elements located at the front of and below said top plate, a metallic drip tray below said heating elements having its front edge terminating considerably to the rear of and below said controlling elements so that heat imparted to said drip tray from said heating elements is not radiated and conveyed to said controlling elements, a vertically arranged baffle at said front edge between the heating and controlling elements, a handle for said tray below said controlling elements accessible at the front of said top plate, and relatively low heat conducting straps connecting said handle with said tray.
- 15 3. An electric range comprising a top plate heating section having a compartment and heating plates located in the top wall of said compartment, an oven section below said top plate section having an oven opening at the front, a door closing said oven, said top plate section having an opening for the admission of cooling air at the front over said oven section, and a baffle over said oven door to deflect hot gases from said oven away from said opening.
- 20 4. An electric range comprising a top plate heating section having a compartment and heating plates located in the top wall of said compartment, an oven section below said top plate section having an oven opening at the front, a door closing said oven, said top plate section having an opening for the admission of cooling air at the front over said oven structure, a drip tray in said compartment below said heating elements sliding outwardly and inwardly through said front opening, and a baffle-like handle for said tray projecting outwardly over said oven opening to deflect hot gases from said oven away from said air admission opening.
- 25 5. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 30 6. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 35 7. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 40 8. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 45 9. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 50 10. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 55 11. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 60 12. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 65 13. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 70 14. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means
- 75 15. A range comprising a cooking top section having top, bottom, side, front and rear walls constructed and arranged to define a compartment, heating means supported in said top wall, controlling elements for said heating means mounted in the front of said compartment back of said front wall, baffles in said compartment shielding said controlling elements from heat radiation from said heating means, said baffles being spaced apart sufficiently far to define a high temperature zone under said heating means

compartment in such manner as to completely prevent passage of air between high and lower temperature zones over the top of said baffle and being spaced from the bottom wall of said compartment, the remaining baffles being spaced from both the top and the bottom walls of said

compartment, openings in said front wall of said compartment above and below said controlling elements, and an opening at the rear of said compartment, the compartment being otherwise substantially closed to the flow of air.

JACOB L. SHROYER.

CERTIFICATE OF CORRECTION.

Patent No. 2,237,795.

April 8, 1941.

JACOB L. SHROYER.

It is hereby certified that error appears in the printed specification of the above numbered patent requiring correction as follows: Page 2, first column, line 9, for the word "directly" read --directed--; same page, second column, line 10, for "greased" read --grease--; page 3, first column, line 7, for "bised" read --biased--; page 4, first column, lines 39 and 40, for "knock out" read --"knock out"--; line 45, for "knock outs" read --"knock outs"--; line 47, for "lower" read --oven--; and that the said Letters Patent should be read with this correction therein that the same may conform to the record of the case in the Patent Office.

Signed and sealed this 27th day of May, A. D. 1941.

(Seal)

Henry Van Arsdale,
Acting Commissioner of Patents.
